UNITED STATES PATENT OFFICE.

GEORGE P. THOMAS, OF GLENNSHAW, PENNSYLVANIA.

METAL-PUNCHING MACHINE.

Application filed May 11, 1923. Serial No. 638,271.

The invention relates to plate-punching machines of the general type in which a templet and work-support is mounted for universal movement in a horizontal plane with relation to a punch, and an index finger is arranged to cooperate with the templet to properly position a plate for punching it.

An object of the invention is to provide a punching machine of this type in which the punch is equipped with a plurality of punching tools adapted to be selectively controlled in coordination with a plurality of index pins, and in which the operation of the punching head is controlled by the index pins.

A further object is to provide a machine of this type in which the plate being punched may be freely moved between punching operations.

A still further object is to improve the general construction of such punching machines to the end that they may be satisfactorily used for punching large plates, and may be used for punching different sized holes in plates of any dimensions.

The invention is illustrated in the accompanying drawings of which Fig. 1 is an elevation of the lower portion of the machine; Fig. 2 a plan view of the portion of the machine shown in Fig. 1; Fig. 3 a vertical sectional view to enlarged scale taken on the line III—III, Fig. 2; Fig. 4 a skeleton plan view of certain operating mechanism, the plane of view being indicated on the line IV—IV, Fig. 1; Fig. 5 an elevation of the front of the punch; Fig. 6 a side elevation of the punch; Fig. 7 a vertical sectional view taken on the line VII—VII, Fig. 5; and Fig. 8 a sectional view to enlarged scale taken on the line VIII—VIII, Fig. 2.

In the practice of the invention a punch having a reciprocating head equipped with a plurality of independently controlled punching tools is associated with a templet and work support which is universally movable in a horizontal plane to move a plate to any desired position with relation to the punching tools. A templet provided with holes spaced as they are required to be punched in the plate is arranged on the support adjacent to the plate, and a plurality of index pins are arranged for registering with the holes in the templet. Each index pin is operatively connected with a

punching tool so that when an index pin is inserted in a hole in the templet the punching tool to which the pin is connected is rendered operative. The reciprocation of the punching head is controlled by a clutch or equivalent device which in turn is controlled by any one of the several index pins. That the dies may not obstruct the movement of the plate after punching operations, provision is made for moving the die holder to and from the plate. Further features of the invention will be explained in connection with the description of the machine shown in the drawings.

In describing the illustrative embodiment of the invention, the templet and work-support will first be explained and thereafter the punch and index finger mechanism.

The templet and work-support comprises a stationary frame 1 on which there is mounted for movements toward and from the punch an intermediate frame 2 which supports a plate and templet receiving frame 3 mounted for movements at right angles to the movements of the intermediate upon the stationary frame. The intermediate frame is provided at its ends with a plurality of grooved rolls 4 which ride upon tracks 5 which may be in the form of angles mounted upon the ends of stationary frame 1, the angles having their roll-supporting edges V-shaped to conform with the grooves in rolls 4. Between its ends the intermediate frame is provided with a suitable number of wheels or rollers 6 having cylindrical faces adapted to ride upon flat faces or edges of angles or tracks 7.

While the intermediate frame may, as is ordinarily done, be pushed to and from the punch, a rack and pinion drive is preferably provided for this purpose, particularly when the frame is long for punching larger plates than have usually been punched with this type of machines. The end angles 5 of the stationary frame are shown as being provided with racks 8, and the intermediate frame with a shaft 9 having pinions 10 at its ends engaging the racks. This shaft 10 may be rotated by a hand wheel 11 attached to it at a convenient position.

The templet and work receiving frame 3 is provided on its lower side with a pair of rails 12 which rest upon grooved rolls 13 mounted on shafts 14 supported by intermediate frame 2. In machines of this type,

particularly when used for punching long and thin plates, the movements of the work-receiving frame are frequently obstructed by the punch dies, both because the plates sag upon the dies and because burrs are formed on the lower faces of the plates by the dies. To render the work-receiving frame freely movable, means are provided for holding it yieldingly upwardly and for urging the plate upwardly. For this purpose the ends of shafts 14 are preferably mounted in bearing blocks 15 arranged for vertical movements in housings 16 attached to the intermediate frame, and springs 17 are arranged in these housings to yieldingly hold shafts 14 and their supporting rolls upwardly. Also, the plate being punched is preferably urged yieldingly upwardly by means of a series of arms 18 pivoted in brackets 19 attached to intermediate frame 2, one end of each arm being provided with a roller 20 and the other end urged downwardly by a spring 21 in the manner clearly indicated in Fig. 8.

Frame 3 is shown as being provided at one end with a plate 22 to be punched and at its other end with a templet 23 provided with holes arranged in the relative positions in which it is desired to punch holes in the plate. Both the plate and templet are broken away to show the parts of the templet and work support. The plate may be attached to frame 3 by means of suitable clamps 24, and the templet by means of a clamp 25, although other suitable clamping devices may be provided for these purposes.

Having reference now to the punch, it may be of the familiar horse-shoe type comprising a frame 26 having a head 27 adapted to be reciprocated in the usual manner by a rotatable shaft 28 driven by a motor 29. The driving connections between the motor and shaft include a clutch 30, which is preferably operated by an electro-magnet or solenoid 30^a in the manner indicated. The punching head 27 is equipped with a plurality of punches 31, 31^a, 31^b and 31^c which may be of different sizes depending upon the different diameters of holes that may be required to be punched. The operability of the punching tools upon the descent of head 27 is selectively controlled by gags in the manner presently to be explained.

Allusion has already been made to the obstruction of the movements of a plate by reason of its contact with a die, and features of construction of the templet and work-support for eliminating or minimizing such obstruction have been explained. To the same end, the punch is preferably provided with means for moving the dies downwardly after, and upwardly before, each punching operation. In the illustrative embodiment of this feature of the invention, shown particularly in Figs. 5, 6 and 7, dies 50, 50^a,

50^b and 50^c are mounted in a die holder 51 which is slidable vertically in punch anvil 52. A wedge-shaped block 53 is mounted in the anvil for horizontal movements which are effected by and in coordination with the mechanism for reciprocating the punching tools. Block 53 may be provided with inclined flanges 54 arranged in corresponding grooves 55 in the sides of die holder 51, and may be provided with horizontal flanges 56 adapted to move in corresponding grooves 57 in the anvil. For reciprocating block 53 horizontally, the end of shaft 28 may be provided with a cam 58 having a groove 59 in which there is arranged a pin or roller 60 extending laterally from an end of a lever 61. This lever is attached to a rock shaft 62 supported by brackets at the side of punch frame 26. At the rear of the gap in the punch frame shaft 62 is provided with an arm 63 pivotally connected to the upper end of a link or pitman 64 which at its lower end is pivotally connected to an arm 65 attached to a rock shaft 66. This shaft may be mounted in brackets projecting from the punch frame below its gap, and is connected to wedge block 53 by an arm 67 and a link 68.

By the chain of connections just described block 53 is moved inwardly to raise die block 51, as the punching head descends, and after the punching operation is moved downwardly to cause the die block to recede below the plate being punched. While it is preferred to provide wedge block 53 with flanges 55 and 57 to positively move the die block downwardly, gravity may be relied upon for this purpose, or other mechanism may be provided.

Turning now to the index pin mechanism, an arm 33 is supported at its rear end by stationary frame 1, and is provided at its forward end with a plurality of reciprocable index pins 34, 34^a, etc. Since the connection extending from each of these pins for controlling one of the punching tools is the same, the connection from but one pin will be explained. The upper end of pin 34 is pivotally attached to a hand lever 35 which is pivoted to a link 36 mounted on arm 33. The inner end of lever 35 is pivotally connected through a link 37 to an arm 38 attached to a rock shaft 39 extending between arm 33 and punch frame 26. Beneath the overhanging portion of the punch frame shaft 39 is provided with an arm 40 pivotally connected to a rod 41 which is attached to a gag 42 for controlling punching tool 31. When lever 35 is depressed to cause index pin 34 to enter a hole in templet 23, rod 41 is, by the train of connections just explained, moved to cause gag 42 to back punching tool 31, so that when the reciprocating punching head moves downwardly this tool will function.

As previously stated, means coordinated with each one of the index fingers is provided for controlling clutch 30. This may conveniently be effected by closing a circuit through clutch-actuating solenoid 30^a. On the top of arm 33 there is mounted a stationary contactor 43, and, cooperating with it, there is a pivotally mounted arm 44 provided with a contactor 45. Arm 44 is attached to a rock shaft 46 to which there is attached a second arm 47 pivotally connected to a link 48. This link is provided with a series of slots 49 each of which receives a pin extending laterally from an arm 70 attached to shafts 39, 39^a, etc. Thus, regardless of which one of these shafts may be rocked by moving one or the other of the index pins into a hole in the templet, arm 44 is depressed to cause contactor 45 to contact with contactor 43 and thereby close a circuit 71 through the clutch-actuating solenoid. The solenoid being thus energized, connection is established between motor 29 and shaft 28 with the result that the reciprocating punching head descends. Upon the release of a hand lever, its index pin is restored to its normal upper position by means of a spring 52 arranged between its actuating hand lever and arm 33. To cause contactor 45 to move upwardly to break the circuit through the solenoid, a spring 73 may be arranged between arm 47 and arm 33 in the manner indicated.

In the operation of the machine a plate 22 to be punched is placed upon frame 3 and clamped to it by means of clamps 24, and a templet 23 is attached to the other end of this frame. A single operator may then move frames 2 and 3 to bring the templet beneath the required index finger for punching the desired hole. For example, when a hole is to be punched by punching tool 31, this is indicated on the templet either by the size of the hole through it or otherwise, and this templet hole is brought beneath index finger 34. Hand lever 35 is then depressed to cause the index finger to enter the hole in the templet. This, through the connections previously explained, causes gag 42 to move back of punching tool 31, and also causes contactor 45 to make contact with contactor 43 to close circuit 71 through clutch-actuating solenoid 30^a. The punching head then moves downwardly to cause punch 31 to perforate the plate. In the same manner the downward movement of any one of the other hand levers 35^a, 35^b and 35^c, controls the functioning of the punches 32^a, 32^b and 32^c, respectively, and likewise controls the operation of the clutch.

Between each punching operation the work-supporting frames 2 and 3 are moved, the former by the rack and pinion connections 8 and 9 and the latter by direct manual movement. The obstruction to these

movements is eliminated by the downward movement of the dies in coordination with the upward movements of the punches, and also by the resilient supports for frame 2 and the spring-actuated arms 18 on frame 70. 2. The machine may therefore be used for punching plates which because of their size and lack of rigidity may sag when supported at their edges, although it will be understood that the invention is applicable to machines for punching plates of a wide variety of sizes and thicknesses.

According to the provisions of the patent statute, I have explained the principle and operation of my invention, and have described it in connection with a machine which I now consider to represent the best embodiment of it. However, I desire to have it understood that, within the scope of the appended claims, the invention may be practiced by other forms of machines than that particularly illustrated and described.

I claim as my invention:

1. In a punching machine, the combination of a punch having a reciprocatory head equipped with a plurality of independently controllable punching tools, means for controlling the reciprocation of said head, a movable templet and work-support, a plurality of independently movable index pins arranged to cooperate with a templet borne by said support, connections extending from each of said pins to said tools whereby a movement of one of the pins renders one of the tools operative, and means actuated by the movements of said index pin for operating said head-controlling means.

2. In a punching machine, the combination of a punch having a reciprocatory head equipped with a plurality of independently controllable punching tools, a clutch for controlling the reciprocation of said head, a templet and work-support mounted for universal movement in a horizontal plane with relation to said punch, a plurality of independently movable index pins arranged to cooperate with a templet borne by said support, connections extending from each of said pins to said tools whereby the movement of a pin renders one of the tools operative, and a single means actuated by the movement of said index pin for moving said clutch to cause the punch head to reciprocate.

3. In a punching machine, the combination of a punch having a reciprocatory head equipped with a plurality of independently controllable punching tools, an electrically operated clutch for controlling the reciprocation of said head, a movable templet and work-support, a plurality of independently movable index pins arranged to cooperate with a templet borne by said support, connections extending from said pins to said

tools whereby the movement of a pin renders one of the tools operative, and a circuit-controlling device for said clutch actuated by the movement of each of said pins.

5. 4. In a punching machine, the combination of a punch having a reciprocatory head equipped with a plurality of punching tools, a separate gag for controlling the operation of each tool, a clutch for controlling the reciprocation of said head, a templet and work-support mounted for universal movement in the horizontal plane with relation to said punch, a plurality of movable index pins arranged to cooperate with a templet borne by said support, levers for operating each of said pins, connections extending from said levers to said gags whereby the movement of a lever throws a gag for one of said tools, and means controlled by the movement of each of said levers for moving said clutch to cause the punching head to reciprocate.

5. The combination with a punching machine, of a templet and work-support comprising a stationary table, an intermediate frame mounted on said table for movements to and from the punch and provided with a plurality of vertically yielding rollers, and a work and templet receiving frame mounted upon said rollers for movements at right angles to the movements of the intermediate frame upon the table, and urged upwardly by said rollers.

6. The combination with a punching machine, of a templet and work-support comprising a stationary table, an intermediate

frame mounted on said table for movements to and from said punch, a work and templet receiving frame mounted upon said intermediate frame for movements at right angles to the movements of the intermediate frame upon said table, and arms borne by said intermediate frame and urged yielding upwardly against a plate borne by said work and templet receiving frame.

7. The combination with a metal punching machine, of a work-support comprising a stationary table provided with not less than three parallel supporting rails, a frame provided with rollers mounted on said rails, two of said rails and the rollers supported by them being provided with cooperating grooves and projections for keeping the frame in alignment, and another of said rails arranged between said two rails having flat roll-supporting faces.

8. The combination with a metal punching machine, of a work-support comprising a stationary table provided with a series of parallel supporting rails, the rails at the ends of said series having convex roll-supporting faces and the intermediate rails of the series having flat roll-supporting faces, and a frame provided with a plurality of series of rollers mounted on said rails, the series of rollers at the ends of the frame having concave rail-engaging faces and the series of rollers intermediate the ends having cylindrical rail-engaging faces.

In testimony whereof, I sign my name. 70

GEORGE P. THOMAS.
